UNITED STATES PATENT OFFICE

CHARLES W. THOMPSON, OF WOLLASTON, MASSACHUSETTS, ASSIGNOR TO HARVEY C. WHEELER, OF BOSTON, MASSACHUSETTS

TOWEL CABINET

Application filed July 27, 1928. Serial No. 295,639.

This invention relates to a cabinet whereby a quantity of clean towels can be conveniently stored in a sanitary way so as to occupy a comparatively small space vertically, and yet be readily accessible.

One of the objects of the invention is to provide a cabinet with exceedingly simple and durable mechanism, compactly arranged, which will hold a large quantity of towels 10 in a small space and automatically push the towels forward to a position where they may be pulled out and used one by one while still connected to the cabinet at one end, thereby preventing misuse of the towels such as shining shoes, dusting furniture, etc., with them.

Another object of the invention is to provide mechanism which will automatically store each strip of toweling after it has been used, so that the soiled towels are kept in 20 orderly fashion without a great waste of space as occurs when soiled towels are carelessly thrown into a receptacle.

In accordance with the rules of practice, reference is made to my co-pending application for towel holders, Serial Number 25 175,137.

With the above and other objects in view which will more readily appear as the nature of the invention is better understood, the same 30 consists in the novel construction, combination and arrangement of parts hereinafter more fully described, claimed and illustrated in the accompanying drawings in which:

Figure 1 is a front view of the towel cabinet.

Figure 2 is a section on line 2—2 of Figure 1 showing the follower and pin compressed part way.

Figure 3 is a section on line 3—3 of Figure 40 1 showing the pin compressed part way.

Figure 4 is a front view of the towel cabinet with the door to the upper chamber raised.

Figure 5 is an edge view of the bunch of 45 towels used in the cabinet.

Figure 6 is a detail view of the fabric towel carrier.

Figure 7 is an enlarged partial section similar to Figure 2 showing the towels in place.

Like numerals and letters of reference indicate corresponding parts in each figure.

As illustrated the cabinet consists of sides 20, having beaded front edges 20a, a back 21, a top 22, a bottom 23, and a partition or shelf 24 dividing the interior into two chambers, 50 an upper 25 and a lower 26, the upper chamber 25 being about one-half the height of the lower one 26. The upper chamber 25 holds the supply of clean towels b, which after use fall inside the lower chamber 26, and when 55 all of the towels have been used they are easily and quickly removed and another bunch readily inserted in their place. Within this upper chamber 25 is enclosed all of the mechanism for automatically pushing the towels 60 to the front of the cabinet.

This cabinet is particularly designed to accommodate a bunch of towels b which are doubled at midlength and stitched or otherwise attached along the fold to a fabric carrier or backing sheet c having buttons or projections d at one end and a slit or button-hole e at the other end. Before inserting in the cabinet each half length of toweling is 70 folded upon itself at approximately its midlength, so that the free end is near the fabric carrier c.

The upper chamber 25 has an upwardly swinging door 27 hinged as shown at 27a, which door extends about three-quarters of 80 the way down the front of said upper chamber, the space being left between the door and the shelf 24 so that the ends of the towels b are exposed and where they may easily be reached and the front towel pulled out and used. A mirror 28 is hingedly attached on the outside of said door as at 28a. Near the lower end of the door 27 holes 29 are cut on 85 each side 27b into which the latches 30 on the sides 20 of the cabinet slip, thereby lock- 90

ing the door which keeps the bunch of towels *b* in an upright position in the cabinet. Holes 31 are punched in the door 27, so that the burrs 32 which result furnish a rough surface 5 to aid in holding the towels in an upright position.

Within the upper chamber 25 is a movable partition or follower 33 which also has holes punched in it so that the burrs 35 resulting therefrom furnish another rough surface for the purpose above explained. This follower 33 is confined within the chamber 25 by means of rods 36 the ends of which project slightly beyond the sides of said follower and come 10 in contact with the beaded front edges 20a on the inside. On each side of the upper chamber 25 near the top are tracks or supports 38 on which the ends of the upper rod 36 rest, thus serving to hold the follower in 15 position vertically. Attached to the back of the follower 33 are two U-shaped pieces 39, having slots 40 cut therein, in which one end of the presser member 41 slides as the partition is moved forwardly and backwardly. This presser member 41 is held in place 20 at the lower inside corners of the upper chamber by inserting its ends 42 into a hole 43 in the small holder blocks 44 which are fastened on the inside at the lower corners of the 25 sides 20. In its normal position the follower 33 is held near the front of the cabinet by means of the springs 45 which are mounted on the presser member 41. There are preferably three slotted holes 46 in the follower 33 into 30 which the buttons *d* of the towel carrier *c* are inserted and held in place.

Underneath the shelf 24 is located all of the mechanism for pulling the used towels to the rear of the lower chamber 26, which consists of a sleeve member 47 attached to the under side of said shelf 24, the body of which sleeve member 47 has a lengthwise opening or slot 48 therein running its full length. Slidably mounted in this sleeve member 47 45 is a flat sliding piece 49a to which is fastened a pin 49 which moves in said slot 48. In their normal position the flat sliding piece 49a and the pin 49 are held at the rear of the cabinet by means of a finger spring 50, the 50 free end of which presses against said pin 49, the other end being fastened to a peg 51 extending downwardly from said shelf 24 at one side. Directly underneath the shelf 24 is a cover 52 which encloses the mechanism 55 described for pulling the used towels out of the way, except the head of the pin 49 which is not so enclosed. This cover 52 has a slot 53 cut therein in which the pin 51 slides, and is held in place in the cabinet at its back end 60 by means of a rod 54 which is enclosed in the back end of said cover with its ends extending beyond the sides and resting upon ears 55 attached to the inner portions of the sides 20 of the cabinet. Said cover 52 is held 65 in place at its front end by inserting it inside

the beaded edge on the shelf 24 as shown at 60.

The lower chamber 26 has a downwardly opening door 56 hingedly attached at the bottom and with springs as shown at 57. This door extends about four-fifths of the way from the bottom to the shelf 24, the space between said shelf and the top of said door 56 being left for the purpose of making it easy for the soiled towels to enter the chamber 26 when the door 56 is pulled open. At each side of said door 56 are wings 58 having upturned edges 59 at the bottom which strike against the inside of the beaded front edges 20a of the sides 20 when the door is fully 70 75 80 85 90 95 100 105 110 115 120 125 130 opened.

The operation of this towel cabinet may be briefly described as follows:

When it is desired to insert a supply of clean towels the latches 30 are pressed inwardly thereby releasing the door 27 which is pushed upwardly out of the way. Then the bunch of towels *b*, which are stitched to the fabric carrier *c*, is placed against the follower 33 with the fabric carrier *c* at the bottom designed to rest directly upon the shelf 24, so that the folds in each half towel are at the top as shown in Figure 7. The buttons *d* on the fabric carrier *c* are slipped into the slotted holes 46 in the follower 33. The bunch of towels *b* is next pressed firmly against the follower 33 causing the presser member 41 to slide upwardly in the slots 40, pushing the follower 33 backwardly until the towels are all in the chamber resting on the shelf 24. To hold them there the door 27 is closed and the latches 30 slip into the holes 29 locking said door. The end of the fabric carrier *c* with the button hole *e* in it is pulled under the shelf 24 and the pin 49 is moved to the front of the cabinet and slipped into the button hole *e*. The finger spring 50 is constantly pressing against the pin 49 forcing it to the back of the cabinet, so that as the towels are pulled out of the upper chamber one by one a portion of the fabric carrier *c* is each time moved under the shelf 24 by the pressure of said spring 50 on the pin 49 constantly pushing it backwards.

The free ends of the clean towels *b* are exposed in the space between the bottom of the door 27 and the shelf 24, so that the user takes hold of the end of the towel and pulls it out, dries himself, pulls the door 56 outwardly and the soiled towel falls inside the lower chamber 26. As the towels are pulled out the bunch in the upper chamber 25 becomes smaller and the follower 33 is constantly pressed toward the front as described, pushing the towels with it so that a clean towel is automatically moved to the front to take the place of the one just used. Inside the lower chamber 26 the opposite automatic movement is taking place as the pin 49 moves backwardly pulling the fabric carrier *c* with it, so that 115 120 125 130

every time a towel is used the pin moves slightly toward the rear. Finally when all of the towels are used the fabric carrier is disengaged from the slotted holes 46 and the pin 49; and the cabinet is replenished with a fresh supply.

What I claim is:

1. A towel cabinet comprising a shelf dividing the cabinet into upper and lower chambers, a door for the upper chamber, a follower, a presser member in back of said follower, and spring actuated means to urge said presser member forward slidably mounted in said follower and located in said upper chamber.

2. A towel cabinet adapted to support a multiplicity of towels attached to a backing sheet comprising a shelf dividing the cabinet into upper and lower chambers, a door for the upper chamber, a follower, a presser member in contact with said follower, spring means to urge said follower forward, said follower, presser member and spring means being located in the upper chamber, and means located in the lower chamber to which said backing sheet is connected to draw the towels into the lower chamber after they have been used, said last mentioned means comprising a sleeve member having a slot therein attached to the underside of said shelf, a pin to slide in said slot, and a spring to urge said pin rearwardly.

3. In a towel cabinet adapted to support a supply of individual towels, means to automatically push the towels forward as they are used, comprising a follower, a piece attached to said follower having a slot cut therein, a bail-shaped presser member adapted to slide in said slot pivotally mounted in the sides of said cabinet, and a spring in contact with said presser member to urge said follower forward.

4. In a towel cabinet, adapted to support a supply of individual towels attached to a backing sheet, the combination of means to automatically push the clean towels forward, and mechanism to which said backing sheet is connected to pull said towels, after they are used, into the cabinet, said means and mechanism being adapted to operate synchronously, said mechanism comprising a sleeve member having a slot therein and a spring actuated pin slidably mounted in said sleeve member to which said backing sheet is attached.

5. A towel cabinet adapted to support a supply of clean towels attached to a carrier, comprising a shelf dividing the cabinet into upper and lower chambers, a door for the upper chamber spaced from said shelf, means located within said upper chamber to automatically push said towels forward as they are used comprising a follower in contact with said supply of clean towels, a piece having a slot therein attached to said fol-

lower, a presser member pivotally mounted to said cabinet and slidably mounted in said slot, a spring attached to said presser member so positioned as to urge said member forward, and means located within said lower chamber to automatically draw said carrier and said towels, after they have been used, into the lower chamber, comprising a sleeve member having a lengthwise slot therein, a pin to which said towel carrier is attached slidably mounted in said sleeve member, and a spring in contact with said pin to urge it rearwardly.
